FIG. 4.

UNITED STATES PATENT OFFICE

2,538,504

GRADE SCORING BOARD

Amos B. Carlile, Indianapolis, Ind.

Application December 2, 1948, Serial No. 63,031

4 Claims. (Cl. 35—9)

1

This invention relates to a device for permitting ready grading and scoring of answers to tests to determine personality qualities, intelligence attributes, and other various aspects relating to the abilities of different individuals as may be determined in answering certain questions or in selecting what may be true and false in respect to certain statements and conditions.

The invention specifically relates to what may be termed a board wherein there are moving elements permitting the applicant of the test to indicate his various answers, and wherein there are a number of different arbitrarily fixed numerals or other characteristics concealed from view of the applicant so that after the test has been completed, the summation of his indications may be readily determined and the proper weight indicated.

A further primary object of the invention is to provide a structure which is exceedingly simple in its make-up, and which may provide means for sealing the various weights given to certain answers, the correct or incorrect answers, and the like, all in a manner which will be readily available to the person who is summing up the scores, simply by breaking a seal or the like.

These and many other objects and advantages of the invention will become apparent to those versed in the art in the following description of the invention as illustrated in the accompanying drawings, in which,

Fig. 1 is a top plan view of the device embodying the invention;

Fig. 2, a transverse vertical section on the line 2—2 in Fig. 1;

Fig. 3, a detail on a slightly enlarged scale in section on the line 3—3;

Fig. 4, a modified form of the invention in top plan view;

Fig. 5, a transverse section on the line 5—5 in Fig. 4;

Fig. 6, a detail in slightly enlarged scale in section on the line 6—6; and

Fig. 7, a detail in section on the line 7—7 in Fig. 4.

Referring to the drawings in which like characters of reference indicate like parts throughout the several views, and particularly to the illustration of the invention as shown in Figs. 1—3, there is provided a board 10 made out of any suitable material such as fiber board, or some more durable material such as a plastic. The board 10 is provided with a plurality of transversely extending and parallel slots 11 sepa-

2

rated one from the other by narrow upstanding ribs 12. These ribs 12 are preferably made to be as narrow as possible and yet provide partitions between the adjacent slots in order that there may be as many slots as possible throughout the entire height of the board 10.

In each of these slots 11 there is placed a slide 13 to be less in length than the length of the slot 11 so that the slide 13 may be reciprocated freely 10 along the slot. Over the board 10 and over the various slides 13, there is positioned a cover plate 14. This cover plate 14 is provided with a plurality of vertically aligned windows herein shown as a major window 15 on the left-hand 15 side and then a plurality of narrow windows spaced to the right therefrom, such windows being designated by the respective numerals 16, 17, 18, 19, 20, 21, and 22. The cover 14 fits over the board 10 and over the adjacent ribs 12 in 20 such manner that the slide 13 may be freely reciprocated between the cover 14 and the board 10.

Each of the slides 13 is preferably provided with a button 23 having a central hole 24 therein 25 to receive any pointed objects such as the point of a lead pencil. This provides ready means for reciprocating the slide 13 along their individual slots 11.

Depending upon the nature of the test to be 30 conducted, and the desired information to be obtained, and the valuations to be placed upon the various answers given, each of these slides 13 is provided with the necessary indicia to give those valuations for the proper positioning of the slide 13 in reference to these various windows. For example, note the slide 13 on which the numeral 23 appears to the left of the button 23. This is the twenty-third slide down from the top, and carries along with it the following 35 notations, first there appears the word "yes," then the word "no," a question mark, a numeral 2, two blank spaces, then the numerals 2 and 1, a blank space, the numeral 6, two more blank spaces, the numeral 5, a blank space, numeral 2, numeral 1, a blank space, a blank space again, the numerals 1, 1, a blank space, the numeral 1, a blank space, the numeral 1, two more blank spaces, the numeral 3, and then six blank spaces, the numeral 8, two blank spaces, the numeral 4, a blank space, and finally the numeral 2 at the 40 extreme end.

All of these words and numerals are spaced in regular sequence in relation to the width and spacing part of the various columns 16—22.

The column 15 as defined by the open window

through the cover 14 remains open at all times and visible to the operator. Likewise the window 16 defining the column next to the right, remains open and visible to the operator at all times. The other columns 17-22 inclusive are covered in any suitable manner such as by the rigid apron 25, removably secured to the board 10 and its cover 14 in any suitable manner. In the present instance, this apron 25 is hinged to the board 10 by means of a length of flexible paper 26. Thus the apron 25 may be left down to cover the windows 17-22 inclusive as indicated by the portion of the cover 25 in the upper part of the view shown in Fig. 1. The apron 25 is preferably held in the closed position to prevent unwarranted inspection of the numerals or indicia appearing in the various columns 17-22 inclusive after the slides have been manipulated to the desired answers as shown in the column appearing through the window 16. The apron 25 is held in this closed position by means of a removable or tearable seal 27. If the seal 27 is intact, it shows that there has been no unwarranted inspection of the columns covered by the apron 25, and on the other hand, if the seal 27 has been broken, then there is evidence that inspection has been had.

Assuming that the test applicant (the testee) has been handed a list of examination questions and a device embodying the structure described herein, the device will be handed to him in that condition wherein all the slides 13 will have been shifted to the desired initial position, by which is meant that, as in Fig. 1, the slides 13 will be positioned to have selectively presented in window 16, a "yes," or "no," or a blank such as the question mark. As applied to Fig. 4, that initial position will expose in window 32, a "zero" space on each slide when all the slides are shifted to the extreme right, or a blank space when shifted to the extreme left.

Then the testee will let alone or shift the slides 13 to cause his desired answer to appear in the respective windows 16 or 32.

It is to be noted that the buttons 23 may be so located that they themselves do not constitute the end of travel limit of the slides since the slide ends may strike the ends of their respective grooves for that purpose. Furthermore the hole 24 of the button 23 in each instance may extend into the slide 13 and the button 23 be reduced in height or even eliminated though it is preferable that the buttons be used for convenience in operating the slides.

Referring to that form shown in Fig. 1, the double columns of figures on the slides 13 appearing in windows 17-22, are employed to denote "plus" and "minus" quantities. For example, the left-hand column in any one of those windows is reserved to display "plus" quantities, while the right-hand column in the same window is reserved to denote "minus" quantities. This is so arranged that the two kinds of quantities are immediately available for separate addition.

If the answer to question number two, Fig. 1, is "no," the applicant will shift slide number 2 to have the word "no" appear in the window 16 accordingly. The answers are given to the questions accordingly throughout the entire series. If the applicant is in doubt and does not want to answer either "yes" or "no" then he can shift the slides to bring question marks into the window 16, that being the position with the buttons 23 shifted to the extreme left-hand side of the window 15.

As above indicated, when the slides are thus shifted, a numeral will appear in any one or different ones of the columns 17-22 inclusive in accordance with a predetermined evaluation to be placed upon the answer. In some instances, for example in relation to the slide 11 bearing the numeral 16 to the left of the button 23, in column 18, there are no indications of any value appearing there. That would be in accordance with the predetermined evaluation to be given to the indicia appearing in 18 when the answer "yes" is given to that question. The various numerals or characters appearing in these columns 17-22, are arbitrarily assigned in accordance with the evaluations to be given in each instance.

After the applicant has completed the answering of the questions, the board is taken by the supervisor of the test, and the seal 27 is broken to have the apron 25 folded back, so that access may be had to the columns 17-22 and the matter appearing therein can be added up in the case of numerals to obtain the desired grade or score as may be wanted from any one of the columns or all of those columns.

Referring now to that form of the invention shown in Figs. 4-7, this structure follows the general layout of the structure defined in reference to Figs. 1-3 inclusive. The structure shown in Figs. 4-7 is preferably designed to be used in answering multiple choice questions. In this instance, the column 28 defined by the vertical opening or window 29 is provided to give access to the various buttons 23 projecting upwardly therein from the slides 13 under the cover 14. The various items from which the applicant selects his answers are numbered and the corresponding numbers appear along the left-hand marginal edge portion of the window 29, herein shown as carrying the numbers 1-45 inclusive to provide for forty-five different items. The board is covered over by the apron 30 and sealed by the seal 31 so that only the vertical window 32 is exposed to the right of the apron 30. The applicant shifts the various slides 13 to cause the numbers to appear in the column or window 32 in accordance with those items which he believes are correct. Then in the windows 33, 34, and 35 normally covered over by the apron 30, will be registered the various characters appearing on the individual slides so as to indicate whether or not the applicant's selection is right or wrong, or whether he has omitted answering all together. For example, column 33 is that column wherein the items have been correctly answered and are so indicated. Column 34 provides for the appearance therein of the numerals indicating the wrong answer or selection, and column 35 provides the indication wherein the applicant has omitted answering all together.

Thus it is to be seen that there is some flexibility in the use of the structure as indicated by the two forms presented, and that the various slides may be given different evaluations in accordance with the questions or items presented to the applicant. Or, conversely, the questions and items may be presented in accordance with predetermined characters or numerals placed upon the individual slides.

Therefore, it is to be seen that I have provided an exceedingly simple, yet very practical device for the purpose indicated, and I do not desire to be limited to those precise forms beyond the limitations which may be imposed by the following claims.

I claim:

1. A grade scoring test board comprising in combination a board having parallel slots extending transversely thereacross; a cover over said board extending over said slots, said cover having a plurality of laterally spaced, vertical windows therein across said slots; a slide in each of said slots; and indicia carried on said slides spaced along the slots to appear in predetermined arrangements through said windows in accordance with elected positioning of the slides as determined by the selection of certain of said indicia to appear in one of said windows; said cover having an operating window therein; means carried by each of said slides available through said operating window to be engaged for shifting the slides; each of said slides being shorter than the length of the slot in which it is carried, whereby the slides are entirely carried within the boundaries of said board in all of the slide shifted positions; said slides being frictionally confined within their slots and under said cover to retain the slides in all positions wherein they are left; and an apron removably carried by said board to cover normally all of said windows except said operating window and one additional window.

2. A grade scoring test board comprising in combination, a board having parallel slots extending transversely thereacross; a cover over said board extending over said slots, said cover having a plurality of laterally spaced apart vertical windows therein to expose different portions of said slots; a slide in each of said slots; indicia carried on said slides to appear in predetermined arrangements through said windows in accordance with elected positioning of the slides as determined by the selection of certain of said indicia to appear in one of said windows; said cover having an operating window therein; means carried by each of said slides available through said operating window to be engaged for shifting the slides; each of said slides being shorter than the length of the slot in which it is carried, whereby the slides are entirely carried within the boundaries of said board in all of the slide shifted positions; said slides being frictionally confined within their slots and under said cover to retain the slides in positions wherein they are left; an apron removably carried by said board to cover normally all of said windows except said operating window and one additional window; and means for sealing said apron in window covering position.

3. A grade scoring board comprising in combination, a board; a cover over the board; a plurality of slides individually shiftably carried side by side between the board and the cover; means between the board and cover confining travel of the slides to directions longitudinally of the slides; said cover having a plurality of windows spaced apart longitudinally of and extending transversely across the slides; an operating element on each of said slides appearing in one of said windows; indicia in spaced zones on said

slides indicating selectable answers to examination questions positioned to appear in a second of said windows; evaluation indicia at spacings along the slides spaced to appear in windows other than said first two windows; said evaluation indicia being correlated with said selectable indicia to appear automatically in said other windows when one of said selectable indicia is caused to appear in said second window; and an apron sealably covering said other windows to leave exposed only said first and second windows; all of said slides having lengths less than that of said board to have their terminal ends remain within the confines of said board length within the limits of travel of said operating element across said one window.

4. A grade scoring board comprising in combination, a board; a cover over the board; a plurality of slides individually shiftably carried side by side between the board and the cover; means between the board and cover confining travel of the slides to directions longitudinally of the slides; said cover having a plurality of windows spaced apart longitudinally of and extending transversely across the slides; an operating element on each of said slides appearing in one of said windows; indicia in spaced zones on said slides indicating selectable answers to examination questions positioned to appear in a second of said windows; evaluation indicia at spacings along the slides spaced to appear in windows other than said first two windows; said evaluation indicia being correlated with said selectable indicia to appear automatically in said other windows when one of said selectable indicia is caused to appear in said second window; and an apron sealably covering said other windows to leave exposed only said first and second windows; said first window being limited in dimension longitudinally of the slides to that distance of travel of the slides for shifting thereof to register the desired selected indicia in said second window; said selectable indicia extending along said slides a distance greater than the width of said second window, whereby only that selected position of the selectable indicia will appear in that second window; all of said slides having lengths less than that of said board to have their terminal ends remain within the confines of said board length within the limits of travel of said operating element across said one window.
